Primary Examiner — Paula Allen Greene*(74) Attorney, Agent, or Firm* — Gokalp Bayramoglu(57) **CLAIM**

The ornamental design for an intelligent earphone, as shown and described.

DESCRIPTION

FIG. 1 is a front view of the intelligent earphone showing our new design;

FIG. 2 is a left side view thereof;

FIG. 3 is a right side view thereof;

FIG. 4 is a top view thereof;

FIG. 5 is a bottom view thereof;

FIG. 6 is a back view thereof;

FIG. 7 is a perspective view thereof; and,

FIG. 8 is another perspective view thereof.

The broken lines in the drawings represent unclaimed portions of the design, which form no part of the claim.

1 Claim, 8 Drawing Sheets(56)
